US0D1077279S

(12) **United States Design Patent** (10) **Patent No.:** **US D1,077,279 S**
(45) **Date of Patent:** **** May 27, 2025**

(54) **MULLION ASSEMBLY**

(71) Applicant: **INTUS Windows LLC**, Fairfax, VA (US)
(72) Inventor: **Rolandas Talalas**, Haymarket, VA (US)
(73) Assignee: **INTUS Windows LLC**, Fairfax, VA (US)
(***) Term: **15 Years**
(21) Appl. No.: **29/873,046**

(22) Filed: **Mar. 24, 2023**

(51) **LOC (15) Cl.** **25-01**
(52) **U.S. Cl.**
USPC **D25/119**

(58) **Field of Classification Search**

(57) **CLAIM**

The ornamental design for the mullion assembly, as shown and described herein.

DESCRIPTION

FIG. 1 is a top perspective view of the mullion assembly shown between two windows;

FIG. 2 is an enlarged view of the area labeled 2 in FIG. 1; FIG. 3 is a partial exploded top perspective view of the area labeled 3 in FIG. 1 without the environment structure;

FIG. 4 is a top plan view of a portion of the mullion assembly shown separate for ease of illustration;

FIG. 5 is a top plan view of a portion of the mullion assembly shown separate for ease of illustration;

FIG. 6 is a top plan view of a portion of the mullion assembly shown separate for ease of illustration;

FIG. 7 is a top plan view of a portion of the mullion assembly shown separate for ease of illustration; and,

FIG. 8 is a top plan view of a portion of the mullion assembly shown separate for ease of illustration.

Any portion of the article not shown forms no part of the claimed design. The broken lines in the drawings depict environmental structures and form no part of the claimed design. The mullion assembly may be used with windows and other structural features in buildings.

1 Claim, 3 Drawing Sheets
